CHAIR OR SEAT

Orville S. Caesar, Chicago, Ill., and Clarence A. Van Derveer, Michigan City, Ind., assignors to S. Karpen & Bros., Chicago, Ill., a corporation of West Virginia

Application June 30, 1930, Serial No. 464,912

6 Claims. (Cl. 155—33)

This invention relates particularly to a chair or seat adapted more especially for use in public conveyances, such as motor busses or the like.

The primary object is to provide chairs or settees with improved means for forming an aisle-chair.

In a preferred embodiment of the invention two chairs disposed on opposite sides of an aisle are equipped with arms which are adapted to be brought into cooperative relation to form an aisle-chair.

The invention is illustrated in a preferred embodiment in the accompanying drawings, in which—

Fig. 1 is a perspective view of aligned chairs or seats, such as may be used in a motor bus; Fig. 2, a broken perspective view, partly in section, illustrating the manner in which adjacent arms of seats bordering on an aisle are brought into cooperative relation to form an aisle-seat; Fig. 3, a vertical sectional view taken as indicated at line 3 of Fig. 2, this view illustrating an arm swinging about a vertical axis; Fig. 4, a vertical sectional view taken as indicated at line 4 of Fig. 2, this view illustrating an arm swinging about a horizontal axis; Fig. 5, a section taken as indicated at line 5 of Fig. 3; Figs. 6 and 7, broken perspective views of the members shown in Fig. 5, illustrating the manner in which the back-forming arm may be locked in either of two positions; Fig. 8, a broken sectional view taken as indicated at line 8 of Fig. 4, this view illustrating the manner in which the seat-forming arm may be locked in vertical position; and Fig. 9, a vertical sectional view, showing a modification.

In the construction illustrated A and A' designate chairs formed on a single base A²; and B and B', chairs formed on a single base B².

The double chairs or seats mentioned are in alignment, but separated by an aisle-space, designated C.

The double chairs are of the same general construction. They are shown as comprising cushions 1 mounted on the base frames and adjustable backs 2 carried by the base frames. The backs are supported on pivots 3 and equipped with adjusting devices 4, enabling the backs to be adjusted rearwardly and forwardly, as desired. No novelty is claimed for the mechanism for effecting adjustment of the backs.

The chairs A' and B' which border on the aisle are equipped, respectively, with arms 5 and 6 which are adapted to be brought into the relation shown in Fig. 2, to form an aisle-chair between the chairs A' and B'.

The arms 5 swings about a vertical axis and affords a back for the aisle-chair; and the arm 6 swings about a horizontal axis and forms a seat for the aisle-chair.

The base frame A² is equipped with ends 7 (one shown) between which the cushions of the seats are interposed, the cushions rising somewhat above the ends as shown in Fig. 3. The end 7 shown in Fig. 3 is equipped at its rear end with a pivot-standard 7^a in which is journaled a vertical pivot-rod 8 having fixedly secured to it supporting arms 8^a which carry the back-forming arm 5.

The standard 7^a is equipped with pivot-lugs 9 having perforations 9^a which received the pivot-rod 8. The lugs 9 are provided on their upper sides with locking-notches or sockets 9^b, either one of which is adapted to receive the locking-lug 8^b with which the corresponding supporting arm 8^a is provided at its hinged-portion.

The notches 9^b are in such position that the back-forming chair arm 5 will be locked either in the position shown in Fig. 2 or in the position shown in Fig. 3, depending upon whether the member 5 is being used as a chair-arm or as a back-forming member.

The lower end of the pivot-rod 8 bears against the short arm of a lever 10 which is carried by a pivot 10^a mounted on the end member 7. The lever 10 is equipped with a treadle-portion 10^b and is normally held in the position shown in Fig. 3 by a spring 11. When it is desired to swing the back-forming member 5, it may be lifted from the position shown in Fig. 3 by means of the lever 10, thus permitting the swinging action to be effected.

The base frame B² is equipped with end-members 12 (one shown). The member 12 adjacent the aisle is equipped with pivot lugs 12^a which support pivots 12^b. The chair arm 6 is carried by supporting arms 13 which have their base portions mounted on the pivots 12^b.

As shown in Fig. 8, one of the arms 13 has its pivot portion equipped with a projection, or stop, 13^a adapted to be engaged by a locking-member 14 carried by a vertical plunger 14^a slidably connected with the end member 12 of the base frame B². A spring 15 interposed between the locking-member 14 and guide-lug 16 serves to actuate the plunger.

When desired, the locking-member 14 may be retracted through the medium of the plunger 14^a, which is equipped at its lower end with a treadle 14^b, thus permitting the arm 6 to be dropped to a horizontal position across the aisle, in which posi-

tion the arms 13 rest upon a shoulder 17 at the upper end of the end-member 12.

The members 5 and 6 may be covered with cushion-pads 5^a and 6^a. That is, these members 5 may be upholstered in some simple way.

In the modification shown in Fig. 9, the pedal-controlled locking device for the arm 5 is dispensed with. In this case, the arm 5 swings about a vertical pivot 5^a of any desired construction; and a vertically movable locking bolt 18, mounted in a guide or keeper 19, is employed for securing the member 5 in the position in which it serves as an arm for the chair. Thus, the bolt 18 engages a perforation or socket with which the end-member 7 is provided. This is a simple form of locking device, rendering unnecessary the vertical movement of the arm provided for in the construction shown in Fig. 3. In the modification, no means is provided for locking the member 5 in the back-forming position. The pivotal connections may be such, of course as to afford a stop which limits the rearward swing of the arm.

The gist of the invention lies in providing two chairs which border on an aisle-space with co-acting convertible arms, one of which arms can be dropped to horizontal position to form a seat-member, and the other of which can be moved or swung to a transverse vertical plane to serve as a back-member.

It will be understood that the improvement permits the chair-arms 5 and 6 to be moved from the arm-rest position and placed in position to form with the main chairs a continuous five-seat arrangement.

The foregoing detailed description is given for clearness of understanding only, and no unnecessary limitations should be understood therefrom, but the appended claims should be construed as broadly as permissible, in view of the prior art.

What we regard as new, and desire to secure by Letters Patent, is:

1. A chair comprising a seat and back, said seat equipped with an end-member having a pivot-standard rising therefrom; an arm equipped with a vertically movable pivot journaled in said standard; a pedal lever adapted to lift said pivot and the arm carried thereby; and interlocking connections between the pivot portion of said arm and said standard.

2. A chair comprising a seat-frame equipped with a horizontal pivot; a convertible arm connected with said pivot and adapted to drop to horizontal position, said arm having a projecting locking member; and a spring-actuated locking member connected with the frame of said chair and normally securing said arm in standing position.

3. A chair as specified in claim 2 characterized by the locking member of said arm having a cam-surface to depress the spring-actuated locking member, whereby said arm may be swung to a vertical standing position without the necessity

of manual retraction of said spring-actuated locking member.

4. In combination: a pair of aligned seats spaced apart to provide an aisle therebetween, said seats being provided adjacent their ends nearest the aisle with movably mounted arm-rests sufficiently long to substantially bridge the aisle when swung thereacross, frame-means supporting said seats and said arm-rests, one of said arm-rests having substantially horizontal pivotal connections at its lower portion with said frame-means on one side of the aisle and adapted to drop into position across the aisle to provide a seat for an aisle chair, and the other arm-rest having at its rear portion substantially vertical pivotal connections with the said frame-means on the other side of the aisle and permitting the second mentioned arm-rest to be swung to a transverse plane back of said aisle seat to provide a back for said aisle seat.

5. In combination: a pair of aligned seats spaced apart to provide an aisle therebetween; convertible arm-rests, respectively, for the adjacent sides of said seats and normally occupying standing positions at opposite sides of said aisle; frame-means supporting said seats and said arm-rests; and connecting-devices between said frame-means and arm-rests serving to support said arm-rests normally in arm-supporting position, one of said connecting-devices providing a substantially horizontal pivotal axis whereby the corresponding arm-rest may be dropped to horizontal position substantially bridging the aisle-space to provide a seat-member for an aisle-seat and the other of said connecting-devices providing a substantially vertical axis whereby the other arm-rest may be swung to a transverse standing position substantially above the rear edge of said seat-member to form a back-rest for the aisle-seat.

6. In combination, a pair of aligned chairs spaced apart to provide an aisle therebetween, said chairs having their ends adjacent the aisle equipped with movably mounted arm-rests sufficiently long to substantially bridge the aisle when swung thereacross, one of said arm-rests having horizontal pivotal connections at its lower portion with one of said chairs and adapted to be dropped into position across the aisle to provide a seat for an aisle-chair, and the other arm-rest having at its rear portion vertical pivotal connections with the other chair and permitting the second-mentioned arm-rest to be swung to a transverse plane back of said seat to provide a back for said aisle-chair, said second-mentioned arm-rest being also vertically movable and equipped with an interlock-member which contacts with interlock-members on the corresponding chair, whereby said arm-rest is fixedly held in either position of adjustment.

ORVILLE S. CAESAR.

CLARENCE A. VAN DERVEER.
